United States Patent Office

Des. 193,033
Patented June 12, 1962

193,033

BOTTLE

Felix V. Waser, Detroit, Mich., assignor to Feigenson, Inc., Detroit, Mich., a corporation of Michigan

Filed Apr. 10, 1961, Ser. No. 64,687

Term of patent 14 years

(Cl. D58—8)

FIG. 2 is a sectional view thereof taken on the line 2—2 of FIG. 1.

The bottle is symmetrical about its vertical center line.

I claim:

The ornamental design for a bottle, substantially as shown and described.
